UNITED STATES PATENT OFFICE.

ROBERT J. BOGUE, OF GOODNIGHT, TEXAS.

FLUID-PRESSURE VALVE.

Application filed June 3, 1926. Serial No. 113,577.

The invention provides a valve mechanism which, in connection with a governor, controls the supply of a motive agent to an engine, whereby its speed may be regulated to the load after the parts have been set to a determinate adjustment.

The invention contemplates a valve including a casing and a fluid pressure controlling element mounted in the casing and adapted to receive a two-fold movement, the one rotary and other axial. The rotary movement of the valve is regular and determines the periods of cutting off the fluid pressure. The longitudinal movement of the valve is variable and determines the duration of the cut off of the fluid pressure.

While the drawings illustrate a preferred embodiment of the invention, it is to be understood that in adapting the means to meet specific needs and requirements the design may be varied and such other changes in the minor details of construction may be resorted to within the scope of the invention as claimed, without departing from the spirit thereof.

For a full understanding of the invention and the merits thereof, reference is to be had to the following description and the drawings hereto attached in which,—

30 Figure 1 is a diagrammatic view illustrative of the invention, as applied to a rotary engine,

Figure 2 is an enlarged sectional view of the valve and governor,

35 Figure 3 is a horizontal sectional view on the line 3—3 of Figure 2, and

Figure 4 is a detail perspective view of the fluid pressure controlling element.

Corresponding and like parts are referred to in the following description and designated in the several views of the drawings by like reference characters.

The numeral 1 designates a rotary engine which may be of any make or type and 2 45 represents a pipe for supplying fluid pressure thereto. The pressure controlling valve is located in the length of the pipe 2 and comprises a casing 3 and an element 4. The casing 3 is of cylindrical form and the fluid pressure controlling element 4 has a snug fit therein and is adapted to receive a rotary movement and an independent longitudinal or axial movement. A tubular shaft 5 extends into the casing 3 and is journaled in the head thereof and has the element 4 adjustably connected thereto, whereby provi-

sion is had for setting the same to a predetermined load and speed. The tubular shaft 5 is adapted to receive a rotary movement and an independent longitudinal movement.

60 For convenience of illustration a bracket 6 is shown attached to the casing of the engine 1 and receives a horizontal shaft 7 which is connected to the shaft of the engine by suitable gearing, such as a sprocket chain 8 and sprocket wheels fast to the shaft 7 and the shaft of the engine. A vertical shaft 9 is geared to the horizontal shaft 7 and passes through the tubular shaft 5 and is stepped in the bottom of the casing 3. The shaft 9 is splined or otherwise connected 65 to the tubular shaft 5 to impart rotary movement thereto and at the same time admit of the shaft 5 moving longitudinally on the shaft 9.

70 Weighted governor arms 10 form connecting means between the two shafts 5 and 9 and are pivoted to a cross head 11 fixed to the shaft 9 and are pivoted to a sleeve 12 adjustably connected to the shaft 5 by means 75 of a set screw 13.

75 The fluid pressure controlling element 4 partakes of the nature of a plug valve in which is formed a longitudinally disposed tapering opening 14 and oppositely disposed lateral ports 15 in communication with the large end of the opening 14 and which are disposed about in line with the fluid pressure supply pipe 2. The ports 15 in conjunction with the opening 14 insure a supply of fluid 80 pressure to the engine when the same is turned on. The tapering opening 14 is centrally disposed so that the outer surfaces 16 of the plug valve are alike and taper inversely to the opening 14, hence the distance from one side of the surface 16 to the opposite side varies at each point in the length of the valve. When the valve 4 is positioned so that the ports 15 just clear the point of communication of the pipe 2 with 85 the casing 3 the fluid pressure is adapted to be cut off for a minimum period and as the valve 4 moves upwardly in the casing 3, under the influence of the governor, as the speed of the engine increases the period of 90 duration of cut-off of the fluid pressure proportionately increases and is maximum when the valve 4 is at the limit of its upward movement. As the valve 4 rotates the opening 14 thereof and the cut off surfaces 16 95 alternately register with the openings 17 in opposite sides of the casing 3 with which the

ends of the pipe 2 connect. As the valve 4 is drawn upwardly in the casing 3 the length of the cut off surfaces 16 in line with the openings 17 increases, thereby increasing the duration of the cut off and in consequence, regulating the supply of the fluid pressure to the engine. The cut off surfaces 16 of the valve 4 similarly taper in the same direction and this is essential to a uniformity of action in cutting off the fluid pressure supply at each one-half revolution of the valve 4. When the engine is at rest the valve element 4 is at the limit of its downward movement in the casing 3 and the ports 15 are about in line with the openings 17 to insure a passage of the motive agent through the valve casing when the same is turned on to the pipe 2 by means of a valve, not shown. As the engine attains the predetermined speed the governor mechanism operates to draw the valve 4 upwardly in the casing 3 and should the speed of the engine increase from any cause the valve 4 will operate to automatically throttle the engine by cutting off the supply of pressure for periods of greater duration by increasing the length of the cut off surface closing the openings 17. Should the speed of the engine fall below the predetermined number of revolutions per minute the governor mechanism will effect a lowering of the valve 4 in the casing 3, thereby decreasing the period of duration of the cut off, thereby resulting in an increased supply of fluid pressure to the engine, whereby to increase the speed thereof. The valve 4 is adjustable on the shaft 5 and is secured in the adjusted position by means of a set screw 4^a threaded into an opening formed in a collar at the upper end thereof.

Having thus described the invention, I claim:

1. A fluid pressure controlling valve comprising a casing having opposed lateral

openings, a valve within the casing and having a medially disposed opening extending both longitudinally and transversely and tapering throughout its length and forming corresponding tapered cut off surfaces, and having lateral ports in the smaller ends of the cut off surfaces leading into the large end of the longitudinally disposed tapered opening, and a governor mechanism for imparting a rotary and a longitudinal movement to the valve. 45

2. A fluid pressure controlling valve comprising a casing having opposed openings in its sides, a valve snugly fitted within the casing and having a medial opening extending both longitudinally and transversely and tapering throughout its length and forming opposite corresponding tapered cut off surfaces and having opposed lateral ports in the smaller ends of the cut off surfaces, concentric shafts extending into the casing and 60 valve and a governor mechanism adjustably connecting the concentric shafts and adapted to impart a rotary and a longitudinal movement to the valve. 65

3. A fluid pressure controlling valve comprising a casing having opposed ports in its sides, concentric shafts within the casing and connected to rotate in unison, the outer shaft being freely slideable on the inner shaft, a plug valve snugly fitting within the casing 70 and formed with a medial opening extending both longitudinally and transversely and tapering throughout its length and adjustable on the outer shaft, and having opposed ports in opposite sides leading into the 75 larger end of the tapered opening, means for securing the valve to the shaft in the desired adjusted position, and a governor mechanism mounted upon the inner shaft and having its weighted arms adjustably 80 connected to the outer valve carrying shaft. 85

In testimony whereof I affix my signature.

ROBERT J. BOGUE. [L. S.]
